UNITED STATES PATENT OFFICE

HOLBROOK WHITEHEAD, OF BALTIMORE, MARYLAND, ASSIGNOR TO J. L. STIFEL & SONS, INC., OF WHEELING, WEST VIRGINIA, A CORPORATION OF WEST VIRGINIA

DESIGN FOR TEXTILE FABRIC

Application filed August 18, 1931. Serial No. 40,885. Term of patent 3½ years.

To all whom it may concern:

Be it known that I, HOLBROOK WHITEHEAD, a citizen of the United States, and a resident of the city of Baltimore, in the county of Baltimore and State of Maryland, have invented the new, original, and ornamental Design for Textile Fabric, of which the following is a specification.

Reference is had to the accompanying drawing forming part thereof, wherein

The figure is a plan view of a piece of textile fabric showing my new design, a complete repeat unit being comprised within the space enclosed by dot and dash lines.

I claim:

The ornamental design for textile fabric, substantially as shown and described.

HOLBROOK WHITEHEAD.
